UNITED STATES PATENT OFFICE.

ELMER M. COBB, OF PORTLAND, MAINE, ASSIGNOR TO WILLIAM B. HAY,
OF PORTLAND, MAINE.

STAPLING-MACHINE.

No. 822,348.

Specification of Letters Patent.

Patented June 5, 1906.

Application filed May 12, 1904. Serial No. 207,643.

To all whom it may concern:

Be it known that I, ELMER M. COBB, a citizen of the United States of America, and a resident of Portland, Maine, have invented 5 certain new and useful Improvements in Stapling-Machines, of which the following is a specification.

My invention relates to a stapling-machine for inserting staples in books, pamphlets, and for other like purposes; and the 10 object of the invention is to improve the stapling-machines now on the market in the direction of simplicity and durability of construction.

15 My improvement includes an improved construction of the swinging anvil over which the staple is formed, by which it is positively drawn back as the staple-driver descends, an improved construction of the 20 cam which drives the driver and the former, whereby a single cam path or groove is used for both parts, and an improved construction of the vertical rod which operates the clutching-dogs, which admits of cheaper 25 method of manufacture.

I illustrate my invention by means of the accompanying drawings, in which—

Figure 1 is a side elevation. Fig. 2 is a section on line $x-x$ of Fig. 1. Fig. 3 is a section of $x-x$ of Fig. 2. Fig. 4 is a rear elevation with the shaft in section. Figs. 5 and 5^a are details of the former and driver, and Figs. 6, 7, and 8 are perspective views showing the operation of the anvil.

35 A represents the bed of the machine, and B' is the standard carrying the most of the working parts. G is the cam on the end of the shaft q' , which is journaled in the standard B'. Immediately in front of the cam 40 and secured to the standard B' is a plate B, in which are slidably mounted the former f and the driver e. These parts are of common construction, the lower end of the driver fitting in a recess in the lower end of the former, so that their lower operative ends 45 are in the same plane. A groove f^2 is provided in the side of this recess to receive the wire of the staple.

The former and the driver reciprocate vertically in a recess in the plate B, and the wire w is fed laterally into the lower portion of this recess through a tubular cutter d, which is screwed into the side of the plate. The inner end of the cutter comes flush with the re-

cess containing the former and as the former 55 descends it shears off the wire to form the staple.

Vertical movement is imparted to the former and driver by means of the cam G, which has on its front face a single path g, in 60 which moves the cam-roll e² of the driver, journaled in a lateral projection e', a similar roll journaled in the lateral projection f³ of the former.

The path g has two concentric sections at 65 different distances from the center, and the two rolls follow each other in this single path and each has the same movement.

The staple is bent over a pointed anvil h', which projects out horizontally from the 70 lower end of a swing-segment h, pivoted at the center.

The anvil h' projects from back of the plate B underneath the end of the driver, and its motion conforms to the movement of the 75 driver, so that it is always in close contact with it.

Motion is given to the anvil by a vertical rack p moving in a vertical guide in the standard B', the rack engaging teeth formed 80 on the edge of the segment h.

The wire is fed to the machine by feed-rolls c c, connected by gears c³ and intermittently operated by means of a ratchet-wheel c', which is actuated by a pawl c². This pawl is 85 pivoted to a reciprocating slide c⁴, mounted on the side of the standard by means of screws c⁵, passing through horizontal slots c⁶.

The slide is thrown first one way and then the other by suitable cam projections c⁸ and 90 c⁹ on the rim of the cam G acting on a cam-roll c⁷ on the top of the slide c⁴. The reciprocation of the slide c⁴ operates to cause the pawl to turn the feed-rolls and feed the wire into the machine just far enough to form a 95 staple, and the feed is timed so that it comes when the driver and former are in their top position.

This feed mechanism forms no part of my invention and any suitable mechanism will 100 answer the purpose.

The rack is moved vertically by means of a roll q, which travels in a path g² on the back side of the cam. The path is so formed that the anvil is always kept in close contact with 105 the lower end of the driver. The staples are clenched by a pair of clenching-dogs i, pivoted below the bed of the machine. They

are formed with two adjacent recesses i' in a well-known manner, and playing vertically in this recess is the upper end of the rod j , having a portion j' milled out below the upper end, leaving a projection j'' to operate the dogs. The rod j is reciprocated vertically by means of a lever o , journaled in a standard o' , the lever being pivoted on the lower end of a slide m , having a cam-roll m' , acted upon by the cam n on the shaft g' in rear of the standard B' . The cam is set so as to throw the slide m down after the staple has been driven and is in position to be clenched.

The operation of the machine is as follows: 15 The wire feeds in over the anvil and below the lower ends of the former and driver, both of which are raised. The former first descends by the action of the cam, cutting off the wire and pressing the ends down over the 20 sides of the anvil to form the staple, the ends lying within the grooves f^2 . (See Figs. 6 and 7.) After the former has reached its lower position it stops and the driver takes up the same motion, forcing the staple down, the anvil drawing back at the same time, so that 25 the wire is always closely held between the

upper surface of the anvil and the lower end of the driver. The staple having been driven in, the clenching-dogs are lifted to a horizontal position, clenching the staple. 30 The former then lifts and the driver follows, ready to receive the next staple.

I claim—

1. In a stapling-machine, the combination of a vertically - reciprocating former and 35 driver each provided with a cam-roll and a cam having a single path in which said rolls travel, thereby imparting to said former and driver like motions, one following the other.

2. In a stapling-machine the combination of a vertically - reciprocating former and 40 driver, a swinging geared segment, an anvil formed on said swinging geared segment, a rack engaging said segment and a cam for reciprocating said rack.

Signed at Portland this 14th day of April, 45 1904.
